UNITED STATES PATENT OFFICE.

JAMES R. SELFRIDGE, OF SAN FRANCISCO, CALIFORNIA, ASSIGNOR TO SELFRIDGE HOLDING COMPANY, OF SAN FRANCISCO, CALIFORNIA, A CORPORATION OF CALIFORNIA.

FORM FOR CONCRETE.

1,163,376.

Specification of Letters Patent.

Patented Dec. 7, 1915.

Application filed July 6, 1915. Serial No. 38,094.

To all whom it may concern:

Be it known that I, JAMES R. SELFRIDGE, a citizen of the United States, and a resident of the city and county of San Francisco, State of California, have invented a certain new and useful Form for Concrete, of which the following is a specification.

The invention relates to forms for concrete building construction and particularly 10 to forms for building columns.

An object of the invention is to provide a cheap and efficient form for use in concrete building construction.

Another object of the invention is to provide 15 a system of forms comprising spirally wound paper tubes.

The invention possesses other advantageous features, which, with the foregoing, will be set forth at length in the following description, 20 where I shall outline in full that form of the invention which I have selected for illustration in the drawings accompanying and forming part of the present specification.

25 The drawings and specification disclose one form of embodiment of my invention, but it is to be understood that the invention may be embodied in other forms without departing from the spirit of the invention, as 30 expressed in the appended claims.

Referring to said drawings: Figure 1 is a horizontal section of a portion of a concrete building taken above a floor. Fig. 2 is a vertical section of the section shown in Fig. 35 1, taken on the line A—A. Fig. 3 is a vertical section taken on the line B—B Fig. 1. Fig. 4 is a vertical section taken on the line C—C Fig. 1.

40 My invention contemplates the use of spirally wound paper tube as the form for concrete columns and a system of form support whereby the paper tubes may be used.

It further contemplates a system of forms in which both floor forms and column forms 45 consist of spirally wound paper tube. The floor is formed with the usual concrete beams and girders intersecting at the top of the column.

In accordance with my invention, a spirally wound paper tube 2 is employed as 50 the column form and extends from one floor to the intersection of the beam and girder of the floor above. Spirally wound paper tube, on account of its construction, forms a rigid, light and cheap mold, which, when

properly used, affords a suitable form for concrete, either when used as a whole for column forms or when split longitudinally into segments for floor forms. The paper forms are water proofed to prevent them absorbing moisture from the fresh concrete and thereby becoming soft and weak, so that they could not retain or support the concrete. 60

The forms 5 for the main transverse and longitudinal concrete floor beams 3—4 are 65 formed of wood and are suitably supported from the floor below by means of posts 6 or other suitable structures, the paper tube column forms 2 not being of sufficient strength to support the weight of the freshly 70 poured concrete floor. The floor forms between the beams 3 consist of a plurality of arched segments of spirally wound tube 7 spaced apart to form the necessary beams 8. The segments 7 are supported along their 75 edges by boards 9 which are in turn supported from the floor below by the posts 6.

The spirally wound paper tubes 2 which form the column forms extend upward to the soffits of the beams 3—4 and the forms 5 are 80 provided with openings at the intersection of the beams so that the column and floor concrete form a monolithic mass. Reinforcing bars or rods 12 extend from the interior of the form 2 through the floor, up into the 85 column form above, and reinforcing rods or bars 13 extend from the form 2 out into the beams 3—4. After the concrete has been poured and set, the supporting frames and the paper tubes may be removed. 90

This construction provides a simple and cheap construction of concrete forms and on account of the low cost of the paper tube is entirely practical. The forms are cheap and the use of a fresh form for each column will 95 not entail any greater expense than the use of wood, which is used repeatedly. A circular column is more efficient than a column of any other cross section, but on account of the large expense of circular wooden molds, 100 square columns have almost invariably been used, in spite of the fact that they are wasteful of concrete. This invention not only provides a simple and cheap system of forms, but permits the use of the more efficient sections of structural elements at a cost which compares favorably with the cost of prior forms. 105

I claim:

1. A form for concrete construction com- 110

- prising floor forms, means for supporting said floor forms and spirally wound paper tube column forms coöperating with said floor forms.
- 5 2. In concrete construction, floor forms, supports for said floor forms extending from a floor below and spirally wound paper tube column forms extending from said floor to said floor forms.
- 10 3. In concrete construction, the combination with a spirally wound paper tube column form, of wooden forms for intersecting beams of the floor above having an aperture therein at their intersection registering 15 with said column form and means for supporting said beam forms.

4. In concrete construction, a spirally wound paper tube column form and a floor form independently supported above said column form.

5. In concrete construction, the combination of a floor form formed of segments of spirally wound paper tube spaced apart transversely, means for supporting said segments and a column form of spirally wound 25 paper tube.

In testimony whereof, I have hereunto set my hand at San Francisco, California, this 21st day of June 1915.

JAMES R. SELFRIDGE.

In presence of—
H. G. PROST.
